United States Patent Office

Des. 198,962
Patented Aug. 18, 1964

198,962

ROTISSERIE OR SIMILAR ARTICLE

Chester H. Wickenberg, Elgin, Ill., assignor to Sunbeam Corporation, Chicago, Ill., a corporation of Illinois

Filed May 27, 1963, Ser. No. 75,074

Term of patent 14 years

(Cl. D81—10)

FIG. 1 is a front elevation view of a rotisserie or similar article embodying the design;

FIG. 2 is a rear elevation view;

FIG. 3 is a side elevation view; and

FIG. 4 is a top view.

The dominant features of my design reside in the portions shown in full lines.

I claim:

The ornamental design for a rotisserie or similar article, as shown and described.
